UNITED STATES PATENT OFFICE

JAMES BARLOW, OF TRENTON, NEW JERSEY, ASSIGNOR TO MERCER
POTTERY COMPANY, OF SAME PLACE.

DESIGN FOR HANDLES FOR COVERED DISHES.

Specification forming part of Design No. **11,361**, dated August 26, 1879; application filed July 28, 1879.
[Term of patent 7 years.]

To all whom it may concern:

Be it known that I, JAMES BARLOW, of Trenton, in the county of Mercer and State of New Jersey, have invented a new and Improved Design for Handles of Covered Dishes, of which the following is a specification.

The design is represented by the accompanying drawings, wherein Figure 1 is a side elevation of a dish and cover, and Fig. 2 is a plan view of the cover.

A is the body of the dish, having handles *a*; and B, the cover, with a handle, *b*. The handles are formed as oblong flat-sided projections, having the ends curved inward from the base to the outer angles, which are formed with scrolls *c*. The handles are solid, except that there is a diamond-shaped opening in the central portion, the edges of which are beaded. At the base of the handles there are leaflets

branching off from each end upon the surface of the disk or cover, as at *d*. This feature may, however, be omitted.

The handle *a* of the cover and handles *b* of the body are alike in their general shape and configuration, except that the handles of the body may project in a direction slightly curved, as shown.

Having thus fully described my invention, I claim as new and desire to secure by Letters Patent—

The design for handles of covered dishes, shown at *a b*, with or without the branching leaflets *d*, and substantially as described.

JAMES BARLOW.
